UNITED STATES PATENT OFFICE.

WILLIAM PFEIFER, JR., OF JERSEY CITY, NEW JERSEY.

ALARM-CLOCK.

1,381,225.

Specification of Letters Patent. Patented June 14, 1921.

Application filed October 28, 1919. Serial No. 334,100.

To all whom it may concern:

Be it known that I, WILLIAM PFEIFER, Jr., a citizen of the United States, residing at Jersey City, county of Hudson, and State of New Jersey, have invented certain new and useful Improvements in Alarm-Clocks, of which the following is a full, clear, and concise description.

The present invention relates generally to improvements in alarm clock construction and is more especially directed to the provision of means for arresting the actuation of the alarm mechanism.

In present types of alarm clocks the means employed for silencing the alarm is usually in the form of a small lever, finger piece or button or the like which is frequently difficult to manipulate and which by reason of its size and disposition on the clock case frequently makes it difficult to locate the same in the darkness or semi-darkness without the employment of some means of illumination. This is especially objectionable where the continued sounding of the alarm will serve to disturb others than the one for whom the signal is intended during the period in which the latter is endeavoring to locate the silencing medium in the dim light, or while he is in the act of providing the necessary illumination to the desired end.

The object of the present invention is to provide a means for arresting the actuation of the alarm mechanism of an alarm clock which may be functioned in a simple and expeditious manner so that the sleeper upon being awakened may at once silence the alarm, whether or not he is in a position to observe the clock.

A further object of my invention is to provide a simple and economical means of silencing the alarm of a so-called alarm clock, which may be cheaply manufactured and attached to a clock or may be readily installed in the manufacture of the clock and which will not detract from the appearance thereof, or interfere with the functioning of the clock mechanism, or the alarm mechanism controlled thereby.

My invention further comprehends a means directed to the aforesaid purpose and possessing the stated characteristics which will be of a size relative to the clock to permit of the ready manipulation thereof to positively engage and arrest the movement of the alarm mechanism, or the means

whereby the alarm mechanism is controlled, said means being capable of coöperating with alarm mechanisms of various types with equal efficiency.

Further objects and advantages of my invention will become obvious as the description proceeds, and in order to afford a clear and comprehensive understanding thereof, I have elected to illustrate and describe it in connection with certain preferred embodiments, although I would have it understood that I do not limit my invention to the specific forms shown herein, reserving unto myself the full range in equivalents, both in structures and uses, to which I may be entitled under my invention in its broadest aspect.

I shall now proceed to describe my invention with reference to the accompanying drawings and then point out with more particularity the essential elements of novelty in the appended claims.

In the drawings:

Figure 1 is a side elevation of a clock partly in section showing my invention applied thereto.

Fig. 2 is a rear elevation of the structure shown in Fig. 1.

Fig. 3 is a top plan view of a clock of the exposed bell type showing my invention incorporated therein.

Fig. 4 is a rear elevation of a clock showing a modified form of my invention applied thereto, and

Fig. 5 illustrates a fragment of the side elevation of a clock showing a further modification of my invention.

Referring now to the drawings in detail in which like characters of reference are employed to designate similar parts throughout the several views, and more especially to the construction shown in Figs. 1 and 2, respectively, 7 indicates the clock casing supported by the usual legs or standards 8. As will be observed the clock shown in Figs. 1 and 2 is of the so-called inside alarm type, the sounding device or bell being indicated at 9, the actuation of the alarm mechanism being controlled by the lever 10 which may be moved to "alarm" and "silent" positions by the finger piece 11. This structure is well known in the art and as it forms no part of the present invention will not be described in detail. Mounted upon the inner face of the casing 7 of the clock, preferably at points below the major diameter thereof,

I provide arms 12 and 13. These arms may be riveted, soldered or otherwise rigidly fastened to the clock casing so as to provide firm mountings for the member 14, by means of which the functioning of the alarm mechanism is governed. This member 14 is preferably annular in configuration and formed from a strip of flat metal, conforming to the configuration of the rear end of the clock casing, and is pivotally connected to the side arms 12 and 13, as shown at 12^a and 13^a. By this means, it will be obvious that the member 14 will be capable of a rocking movement toward and away from the face of the clock on its fulcrum points provided by the aforesaid pivots 12^a and 13^a.

In order to render the alarm mechanism operable at the set time, the finger piece 11 is usually moved to the right, looking at Fig. 2, the movement of the said finger piece in reverse direction serving to "silence" the alarm. Therefore, in order to move the lever 10 in the proper direction for rendering the alarm mechanism inoperative, through the medium of the member 14, I have found it expedient to provide the right hand extremity of the lever 10 with a downwardly dependent flange 10^a, which is adapted to be engaged by the ends of the levers 15 and 16 which are pivoted together as shown at 17. The lever 15, as will be noted, is pivotally mounted within the clock casing at 18, while the lever 16 is pivotally connected with the annular member 14, as shown at 19.

From the construction thus far described, it will be manifest that when the finger piece 11 is moved to its extreme right position, the dependent flange 10^a of the lever 10 will abut against the ends of the levers 15 and 16 and move them on their pivots whereby the annular member 14 assumes the position shown in Fig. 1. When it is desired to silence the alarm, all that is necessary is to grasp the annular member 14 at any part above its fulcrum points, and move it toward the back or rear of the clock casing. This movement, as will be obvious, will cause the pivoted ends of the levers 15 and 16 to contact with the dependent flange 10^a and move the lever 10 toward the left, or to "silencing" position. In the construction shown in Fig. 3 wherein I have illustrated my invention applied to a clock having an exposed bell 7^a, the annular member 14 in lieu of the coöperating levers 15 and 16, is provided with an arm 20 riveted or otherwise secured thereto at 21 the inner end of which is adapted to ride through a guide 23 located upon and secured to the outer surface of the clock casing by any suitable means. The inner end of the arm 20 is bifurcated or formed with a V-shaped cut-out 24 whereby the oscillation of the clapper arm 25 may be arrested by the move-

ment of the annular member 14 inwardly or 65 toward the rear of the clock casing.

In the modification shown in Fig. 4, in lieu of the annular member 14, I employ a semi-annular member 26 which is pivotally mounted at 27 on the supporting arms 28, 79 the functioning of the member of this form being similar to that of the member 14 with the exception that the gripping or useful surface thereof, is somewhat decreased or lessened.

In Fig. 5, in lieu of making the annular member 14 of flat strip metal, I have shown it made of wire or the like as indicated by reference numeral 29, suitable ears 30 and 31 being provided for pivotally connecting 80 the said member with its supports and the operating levers.

From my disclosure, it will be evident that the provision of the annular member 14 or an equivalent structure will afford a readily 85 accessible means for rendering the alarm mechanism inoperative so that the sounding of the alarm may be stopped by simply grasping the clock and the member 14 at substantially any part of the peripheries 90 thereof and moving or pressing the said member toward the rear of the clock casing.

While I have shown and described my invention with reference to the accompanying drawings, it is obvious that various 95 changes in details of structure may be made without departing from the spirit and scope thereof.

I claim—

1. The combination with a clock having 100 an alarm and mechanism actuatable to function said alarm, of means for arresting the operation of said mechanism, said means embodying a device located exteriorly of the clock casing and connected thereto, so as to 105 be capable of movement toward and away from the clock casing, and means carried by said device adapted for engagement with an element of the alarm mechanism to render the same inactive when said device is moved 110 in one of said directions.

2. The combination with a clock having an alarm, actuating mechanism therefor, and means for controlling said actuating mechanism of a device for operating said controlling means to silence the alarm, said device including an annular member mounted exteriorly of the clock and a lever carried thereby, adapted to engage said controlling means, said annular member being capable 115 of movement relatively to the clock.

3. The combination with a clock having an alarm, actuating mechanism therefor and means for controlling said actuating mechanism, of a device adapted to function said 120 controlling means, said device embodying a member mounted on said clock and capable of movement relatively thereto, a lever piv-

totally connected to said clock, a lever having pivotal connection with said member, said levers being pivotally connected to each other and formed for engagement with said controlling means upon the movement of said member, whereby said controlling means will function to arrest the movement of said actuating mechanism.

4. The combination with a clock having an alarm and mechanism for actuating said alarm, of means for rendering said mechanism inoperative, said means embodying a member located exteriorly of the clock and having spaced points of connection with the casing thereof whereby said member will be capable of movement relative to the clock casing, and means carried by said member adapted to render said actuating mechanism inoperative.
5. The combination with an alarm clock having alarm actuating mechanism and controlling means therefor, of means for operating said controlling means to render said mechanism inoperative, said means embodying a pair of arms supported by said clock and extending exteriorly thereof, an annular member of a diameter substantially co-extensive with that of the clock fulcrumed on said arms, a lever pivotally mounted on said clock, a lever having a pivotal connection with said member, said levers being pivotally connected and formed for engagement

with said controlling means when said member is moved toward the clock.

6. The combination with an alarm clock having an alarm, alarm actuating mechanism and a device for controlling the functioning of said mechanism, of means for operating said controlling device to render said mechanism inoperative, said means embodying a pair of arms extending from the rear of the clock, an annular member of a diameter substantially co-extensive with that of the clock pivotally mounted on said arms on an axis lying in a minor diameter of said member, a lever pivotally connected to said clock, a second lever having a pivotal connection with said member, said levers being pivotally connected and adapted to engage said controlling device when said member is moved on its axis toward the clock to function said device to render said mechanism inoperative.

7. The combination with a clock having an alarm and actuating mechanism therefor, of means for rendering said mechanism inoperative, said means embodying an annular member located exteriorly of the clock and connected to the casing thereof, and means carried by said member adapted to function to render said actuating mechanism inoperative upon the movement of said member toward said clock.

WILLIAM PFEIFER, JR.
